UNITED STATES PATENT OFFICE.

FRANCIS W. GIBSON, OF WEST ROXBURY, MASSACHUSETTS, ASSIGNOR TO THE H. D. BEACH COMPANY, OF COSHOCTON, OHIO, A CORPORATION OF OHIO.

TABLE.

Application filed July 21, 1926. Serial No. 123,869.

This invention relates generally to furniture, and particularly to a table or stand formed of sheet metal, but it is understood that other materials may be employed.

5 One of the objects of this invention is to provide a stand or table of simple and inexpensive construction.

A further object is to provide an article of furniture which may be readily constructed from sheet metal parts in which the parts of the body portion are of uniform construction, and in which the parts forming the top portion are also of identical or uniform construction.

15 A further object is to provide an article of furniture such as a stand or table, in which a simple and inexpensive construction is provided for securing a two-part top in position, so as to prevent movement of the 20 top relative to the body portion of the table, in any direction in a horizontal plane.

Other objects and advantages will be apparent from the following description and the accompanying drawings.

25 In the accompanying drawings one preferred form of the invention is shown for purposes of illustration:

Fig. 1 is a front elevation of the table or stand.

30 Fig. 2 is a side elevation of Fig. 1.

Fig. 3 is a top plan of Fig. 2.

Fig. 4 is a bottom plan of Fig. 1.

Fig. 5 is a fragment of a section taken on the line 5-5 of Fig. 3, showing the 35 operating and interlocking notch portions of the rib of the top, and one side of the table or stand.

Fig. 6 is a fragment partly in section taken on the line 6-6 of Fig. 4.

40 In the preferred form shown, the table or stand comprises a plurality of side portions 1, 2, 3 and 4. Each side is provided with a bent edge portion 5, 6, 7 and 8. The bent edge portion of any one side is adapted

45 to overlie the unbent edge of an adjacent side portion and the sides are held in proper relative position by a suitable securing means, such as a nut and bolt 9. It is to be noted that each of the four sides of the body

50 portion of the stand in the form shown, is of the same size and construction, that is, the body portion is made up of a number of duplicate parts. This is a very desirable feature, as it enables the table to be economically manufactured. The top for the

stand is composed of two parts 10 and 11, which parts are also duplicates and of uniform size and construction.

A means is provided in the construction of the top of the table, whereby movement of the top parts, in a rotary, longitudinal or lateral direction, relative to the body portion is prevented. The top portions of the table are held in the proper position relative to the body portion, without the necessity of use of independent securing means, such as screws, bolts or other fastenings. In order to hold the top portions in proper fixed position relative to the body portion, each of the top portions 10 and 11 is provided with bent edge portions 12 and 13 extending throughout the length of the top portions, so that when the bent edge portions are abutted against each other, a central downwardly-extending rib is formed which extends across the under side of the top formed by the portions 10 and 11. At those points in the bent edge portions 12 and 13 of the top, where said portions cross or overlie the opposite sides 1 and 2 of the body portion, a notch 14 is formed in the bent edge portions, which notch extends part way across the width of the bent edge portion. At the point in the opposite sides 1 and 2 where said side portions are crossed by the turned edge 12 and 13 of the top portions 10 and 11, said sides 1 and 2 are also provided with a notch 15, the depth of which is equal substantially to the difference between the depth of the notch 14 in the bent edge portion of the top, and the total width of the turned edge portion of the top. Such a construction, permits an interlocking and cooperating action between the notches formed in the sides and in the turned edge of the top portions, so as to prevent relative rotary, longitudinal or lateral movement of the top in a horizontal plane.

While one preferred form of the invention has been shown for purposes of illustration, various changes and modifications may be made by those skilled in the art without departing from the spirit and scope of the invention as defined in the appended claims.

What I therefore claim and desire to secure by Letters Patent is:

1. A table comprising side portions of the same size and form, each side having a bent edge adapted to overlie and connect

with an adjacent side, a two part top, each part being of similar form and having a turned edge portion adapted to form a central rib when the turned edge portion of each of the top parts are abutted against each other, the turned edge portion of each top part having a plurality of notches extending part way across said turned edge portion, the opposite sides of said table also having notches in the upper edge thereof adapted to receive the turned edge of each of the top portions, the notches in the side portions being of a depth less than the width of the turned edge portion of the top, said notches in the sides being of a width equal to at least twice the thickness of the turned edge of the top portion.

2. An article of furniture comprising a plurality of sides of corresponding form, each side including a flat portion and a bent edge portion adapted to overlie the adjacent side portion, means cooperating with the turned edge portion and an adjacent side for holding the parts in proper relative position, 25 a top having a downwardly extending rib projecting from the under side and disposed centrally of the top and means arranged to prevent either rotary, longitudinal or lateral movement in a horizontal plane between the top and sides, said means including notches spaced in the rib portion of the top and co-

operating notches in the opposite sides of the article.

3. An article of furniture comprising a plurality of sides, means for securing the sides in position, a two part top for said sides, each part having a turned edge portion, means for holding the two portions of the top in position on the sides so as to be held against rotary longitudinal or lateral movement in a horizontal plane relative to the sides, said positioning means including a plurality of spaced notches formed in the turned edge portion of each of the top portions, said notches extending part way across said turned edge portion of the top, and notches formed in opposite sides of the article, said notches being of a depth equal substantially to the difference between the depth of the notch in the turned edge of the top portion, and the total width of said turned edge portion of the top, whereby that portion of the turned edge of the top between the end of the notch in the turned edge of the top and the main top portion, may fit within the notch formed in the side portion so as to form an interlocking effect preventing any relative movement between the top and the sides in a horizontal plane.

In testimony whereof I affix my signature.

FRANCIS W. GIBSON.
